UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

COMPOSITE DUMP-CAR.

1,285,614.

Specification of Letters Patent.

Patented Nov. 26, 1918.

Application filed July 29, 1918. Serial No. 247,089.

To all whom it may concern:

Be it known that I, ARGYLE CAMPBELL, a citizen of the United States, residing at Chicago, in the county of Cook and State of Illinois, have invented a certain new and useful Improvement in Composite Dump-Cars, of which the following is a full, clear, concise, and exact description, reference being had to the accompanying drawings, forming 10 a part of this specification.

This invention relates to improvements in composite dump cars.

One object of the invention is to provide a composite steel and wood dump car of efficient and economical design. Another and 15 more specific object of the invention is to provide a composite car of the type above indicated wherein the car is provided with drop bottom doors having the operating 20 mechanism therefor located above the floor level and so arranged as to obtain maximum load carrying capacity, and wherein the sides of the car provide an exceptionally 25 strong load carrying element of the structure.

In the drawing forming a part of this specification, Figure 1 is a side elevation of a little less than one-half of a car embodying my improvements; Fig. 2 is a part end elevation, part transverse vertical sectional view of the car shown in Fig. 1, the section being taken intermediate two of the car side stakes, and Fig. 3 is an enlarged detailed 30 sectional view illustrating more particularly 35 the construction at the lower portion of the side wall of the car where the same joins the cross bearers of the under frame. In said drawing, the car is shown as provided with a girder, built-up center sill as indicated at 40 10, bolsters 11, cross bearers 12, preferably of pressed metal, pressed metal side stakes 13-13, end walls 14 and pivoted, side dumping drop bottom doors 15-15, the latter being hinged along their inner edges to the 45 center sill as indicated at 16 in Fig. 2.

Each side wall of the car is formed by a series of planks as indicated at 17, 18 and 19, together with an angle upper truss member 20 and a lower angle truss member 21. The 50 side wall consists of the main vertical section formed by the plank 12, an inwardly and downwardly inclined section formed by the planks 18, and a narrow vertical section formed by the planks 19, terminating at the 55 floor level.

To strengthen the connection between the

stakes and the cross members of the car under frame, I employ pressed sheet metal stake fillers as indicated at 22 and illustrated most clearly in Fig. 3. These fillers are riveted to the cross members of the under frame and to the side stakes 13 and furthermore form supports on which rest the lower truss angles 21.

For operating the doors 15, I employ on 65 each side of the car a longitudinally extending operating shaft 23, mounted in suitable bearing brackets 24 that are secured to the fillers 22 and at the end of the car. In this connection it will be understood that the fillers are suitably perforated to accommodate the shaft. For each door 15 there are provided two sets of linkages, each set comprising a hook element 25, a short link 26, links 27 and 28 and a terminal link 29 pivotally 70 connected to a drum 30, mounted on the shaft 23. This form of linkage mechanism is well known and need not be described more specifically.

Along the lower edge of the section 19 of 80 each side wall I provide another angle 31 as shown in Figs. 2 and 3, said angle 31 resting on top of the cross members of the under frame and also secured to the fillers 22. On the outer sides of the wood portions of the 85 side walls I provide a series of diagonal bracing members as indicated at 32 and 33, the arrangement being such in the construction illustrated in the drawing that the diagonal members act as tension elements, although it is evident that their position might be reversed and the same placed under compression.

By referring to Figs. 2 and 3 it will be noted that I place the operating shafts 23 95 very close to the side stakes and above the floor level of the car, and some of the elements of the flexible connections are disposed partly outside of the vertical planes corresponding to the outer surfaces of the 100 wooden section 17 of the car sides. In this manner, I am enabled to reduce the space required for the door operating mechanism and thereby increase the load carrying capacity of the car. This same object is further promoted by the fact that the side wall of the car, particularly the section 17, is designed to carry a large portion of the load by reason of the employment of the upper and lower truss members 20 and 21 105 and supporting said section 17 of the side wall on top of the stake fillers 22; in other

- words, the side walls of the car constitute girders for carrying the major portion of the load and I am enabled to obtain substantially as large a capacity for the car 5 with my composite construction as has ever been obtained in an all-steel construction, and a greater capacity than has heretofore been possible in a wood or composite car of the general type disclosed in the drawing.
- 10 Although I have herein shown and described what I now consider the preferred manner of carrying out my invention, the same is merely illustrative and I contemplate all changes and modifications that 15 come within the scope of the claims appended hereto.
- I claim—
1. In a dump car, the combination with the under frame, side stakes, and pivoted 20 floor doors, of side walls, each of said side walls comprising an upper metal truss member, a lower metal truss member, the latter being located above the floor level, and wood planks between said truss members 25 and all secured to said side stakes, each side wall having also an inwardly and downwardly inclined extension, and door operating mechanism located beneath said inclined extensions.
  - 30 2. In a dump car, the combination with the under frame, side stakes and pivoted side dumping floor doors, of composite side walls secured to said side stakes, and side stake fillers located at the bottom of the 35 side walls and uniting the side stakes with the cross members of the under frame, said fillers also serving as supports for the side walls.
  3. In a dump car, the combination with 40 the under frame, comprising center sill and cross members, of side stakes, pressed metal fillers located at the junction of each side
- stake and cross member of the under frame, said fillers extending above the floor level of the car, longitudinally extending angle 45 irons secured to the inner sides of the side stakes of the car and resting upon the tops of said fillers, upper angle irons secured to the tops of the side stakes on each side of the car, wood planking also secured to the 50 side stakes and extending between said upper and lower angle irons, and diagonal bracing members, said angle irons, planks and bracing members constituting girders adapted to carry the major portion of the 55 load of the car.
4. In a dump car, the combination with the under frame comprising a center sill and cross members, of side stakes secured to the outer ends of the cross members of the under 60 frame, floor doors pivotally attached along their inner edges to the center sill, fillers uniting the side stakes with the respective adjacent cross members of the under frame, said fillers extending above the floor level, 65 a longitudinally extending operating shaft on each side of the car passing through said fillers and located above the floor level and disposed closely adjacent the respective side stakes, flexible connections from said 70 shafts to the doors, and composite side walls, each of said side walls having a lower inwardly and downwardly inclined portion forming a shield for the door operating mechanism, each side wall also including a 75 lower truss member resting upon the tops of the corresponding side stake fillers.
- In witness that I claim the foregoing I have hereunto subscribed my name.

ARGYLE CAMPBELL
